UNITED STATES PATENT OFFICE.

JOHN W. CLARK, OF PROVIDENCE, RHODE ISLAND.

RAIL JOINT.

Application filed August 25, 1922. Serial No. 584,308.

To all whom it may concern:

Be it known that I, JOHN W. CLARK, a citizen of the United States, residing at Providence, in the county of Providence and State of Rhode Island, have invented certain new and useful Improvements in Rail Joints, of which the following is a specification.

This invention relates to an improved form of rail joint and constitutes an improvement upon the structure shown and described in my copending application, Serial No. 536,749 filed February 15, 1922.

One object of the invention is to provide a joint wherein the meeting ends of the rails are supported by a seat having inclined ends which engage inclined faces upon depending lugs carried by the fish plates, the inclination of the seat ends and faces of the lugs being such that the faces of the lugs contact with the inclined ends of the seat throughout substantially the entire area of the seat ends, the lugs being forced into gripping contact with the seat ends by screws or other suitable fastening means whereby the strain or pressure upon the seat is communicated directly to the lugs and protects the screws or other fastening means from undue strain.

In the structure shown, described and claimed in my copending application above referred to, I have made use of a rail joint structure which comprises fish plates for attachment to opposite sides of the rail ends, each of which is provided with a depending lug having an inclined inner face, the inclined inner faces of said lugs being oppositely positioned; a seat having inclined ends positioned between the depending lugs, the angle of inclination of the seat ends being somewhat less than the angle of inclination of the faces of the lugs whereby the lugs normally contact with and exert pressure upon the seat below the central portion of the seat; a truss member underlying the seat to assist in supporting the same; and screws threaded into opposite ends of the seat and extending through the depending lugs to draw the depending lugs into gripping engagement with the inclined ends of the seat.

I have found that while the above structure is admirably adapted for use under certain conditions, the truss member may be dispensed with under certain conditions of

use and where the truss member is not employed in the combination materially increased efficiency may be obtained by giving the ends of the seat and the inner faces of the lugs substantially the same inclination from the vertical whereby when the faces of the lugs are forced into contact with the seat ends they will bear thereagainst throughout a substantial portion of the seat ends, which bearing portion may be located mainly adjacent to the upper portion of the seat or at least above the center of gravity of the seat, thus effecting a relatively broad bearing for the seat ends upon the inclined faces of the lugs and communicating the strain or pressure exerted upon the seat directly upon the depending lugs to protect the screws or other tensioning means from injury and direct the strain upon the parts best adapted to support the same. At the same time the inclination of the faces and seat ends will tend to constantly urge the seat upwardly into contact with the rail ends under the influence of the tension exerted by the screws or other fastening means employed.

Referring to the drawings:

Fig. 1 is a side elevational view of the improved rail joint.

Fig. 2 is a transverse vertical sectional view, taken along the line 2-2 of Fig. 1.

Fig. 3 is a view similar to Fig. 2 showing a slightly modified structure.

Fig. 4 is a view similar to Fig. 2, showing a further modification.

Fig. 5 is a detail sectional view taken along the line 5-5 of Fig. 3.

Fig. 6 is a side elevational view showing one form in which my invention may be applied to street car rails, and

Fig. 7 is a sectional view taken along the line 6-6 of Fig. 7.

In the embodiment of the invention illustrated in Figs. 1 and 2, 1 and 2 designate respectively adjacent rails the abutting ends of which are indicated by the numerals 3 and 4 respectively. The cross-tie supporting the ends of the rail 1 adjacent to the joint is numbered 5, while the correspondingly positioned cross-tie for supporting the rail 2 is indicated by the reference character 7, the fastening means for securing the rails to their respective cross-ties being numbered 6 and 8 respectively.

Fish plates 9 and 10, of symmetrical form

are positioned upon opposite sides of the meeting ends of the rails 1 and 2 and secured to each other through the web portions 11 of the rails by means of a plurality of bolts 12. Except for the depending lug, each fish plate may be of uniform or substantially uniform cross-sectional configuration throughout its length, corresponding to the section thereof shown in Figs. 2, 3 and 4, thus permitting the fish plates to be formed by rolling between suitably formed rolls after a manner well known in the art, or by pressing, or other suitable means. If found desirable under certain conditions of use the fish plates may each be provided with a central thickened portion extending inwardly towards the rail web from the main body portion of the fish plate and located adjacent to the meeting point of the rail ends to enable the fish plates to more firmly grip the rail ends as the bolts 12 are tightened. Each of the fish plates is formed to provide throughout its length the usual bearing head 14 and the usual inclined foot flange 15 for suitably engaging the head and base flange respectively of each rail. A depending lug 16 is formed upon each of the fish plates centrally thereof and is provided with an inwardly inclined face 17 for contact with one of the inclined ends 18 of a seat 19 positioned beneath the meeting ends of the rails. The angle of inclination of the faces 17 of the depending lugs as shown in Fig. 2 is substantially the same as the angle of inclination of each end 18 of the seat 19 whereby the inclined faces of the depending lugs may contact with the seat ends throughout a substantial portion of the same when the depending lugs are held in engagement with the seat ends by means which will be more fully described hereinafter. Each of the oppositely positioned depending lug 16 is provided with a round or oblong opening 20 for the reception of a screw 21 which is threaded into a suitable opening formed in the end of the seat 19.

The lower end portion of each of the depending lugs 16 is preferably thickened somewhat as indicated at 22 and the outer face thereof is inclined inwardly both above and below the oblong opening 20 to form seating surfaces 23 and 24 respectively for the upper and lower edges 25 and 26 of a washer 27. The inclined outer face of each lug as shown in Fig. 2 of the drawings permits the central portion of the washer to be sprung inwardly slightly as the head 28 of each screw 21 bears thereagainst when the screws 21 are tightened, and resiliently forces the corresponding lug into contact with the adjacent end of the seat, the inclined inner faces of the lugs simultaneously acting upon the inclined ends of the seat to urge the seat upwardly and into contact with the rail ends.

Thus it will be seen that while the oblong opening 20 in each lug permits the seat to be slightly depressed as greater pressure is exerted upon the rail ends in consequence of the passage of a train thereover, the strain 70 incident thereto is communicated from the seat directly to the depending lugs by reason of the large surface of contact between the seat ends and the inclined faces of the lugs, and immediately upon the release of such 75 pressure the seat is again forced upwardly into contact with the rail ends by reason of the inclined faces of the lugs pressing against the inclined seat ends and this action is increased by the tension under which the 80 washers are placed as the screws 21 are tightened.

In the form of the invention shown in Fig. 3 of the drawings the fish plates 9 and 10 are formed as previously described and secured to the rails by bolts 12 passing through the web portions 11 of the rail ends, each fish plate being provided with a depending lug 16 having an inclined inner face 30 for contact with one of the inclined 90 ends 31 of the seat 32. In this form of the invention the angle of inclination of the seat end is slightly greater than the angle of inclination of the corresponding inner face of the depending lug for a purpose which will 95 be more fully described hereinafter. Each lug is provided with an oblong opening 33 for the reception of a bolt 34 which passes beneath the seat and lies partially within a recess 35 extending across the lower face 100 of the seat.

The bolt 34 has a head 36 which bears against a washer 37 located outwardly of one of the depending lugs, while a nut 38 threaded upon the opposite end of the bolt bears 105 against a similar washer 37 located outwardly of the other depending lug. Each of the depending lugs is provided upon its outer face with an inwardly inclined surface 39 adjacent to the upper edge of the washer 37 and a second inclined surface 40 located adjacent the lower edge of the washer, the angle of inclination of the surface 40 from the vertical being somewhat greater than the angle of inclination of the 115 surface 39. Each of the washers 37 may be provided with a curved shoulder 41 for contact with the inclined surface 40 to increase the upwardly creeping action of the washers when pressure is exerted thereon by tightening the nut 38 on the bolt 34.

In this form of the invention the slight difference between the inclination of the ends of the seat and the corresponding inclined faces of the lugs is preferably only 125 sufficient to permit the depending lugs to spring inwardly slightly as the ends of the seat wear and as greater tension is placed on the lugs by tightening the nut 38 so that the inner inclined faces of the depending 130

lugs shortly contact with substantially the entire surfaces of the inclined ends of the seat. The use of the bolts 34 as a substitute for the screws 21 previously described is in 5 itself an optional construction which has the advantage of being of somewhat simpler construction and more readily assembled. The difference in the inclination of the seat ends and the faces of the lugs is more readily 10 adapted for use in connection with the bolt for connecting the depending lugs than with the screws shown in Fig. 2 by reason of the fact that the bolt of necessity occupies a lower position relative to the seat. However, 15 the variation in the angle of the seat end and lug may be utilized in connection with the fastening or tensioning screws shown in Fig. 2, particularly where the screws are located a substantial distance below 20 the upper surface of the seat.

In the form of the invention shown in Fig. 4 of the drawings the fish plates 9 and 10 are formed as described in connection with the preceding figures and are secured to the 25 rail by bolts 12 passing through the web portions 11 of the rail ends, each fish plate being provided with a depending lug 16 having an inclined face 48 for contact with one of the inclined ends 41 of the seat 42.

In this form of the invention as in that shown in Fig. 3 the angle of inclination of each end 41 of the seat is shown as being slightly greater than the angle of inclination of its corresponding depending lug. Each 30 depending lug is provided with an oblong opening 43 for the reception of a screw 44 which is threaded into a suitable opening formed in one end of the seat 42, while a head 45 carried by each screw is adapted to bear against the outer surface of a washer 46 in order to force the lugs into gripping engagement with the seat upon tightening the screws. Each washer 46 is provided with an inturned extension 47 adapted to 35 bear against the lower face of the seat when the head 45 of the corresponding screw presses against the outer face of the washer and thus assist the force exerted by the inclined faces of the lugs bearing against the 40 inclined ends of the seat in urging the seat upwardly into contact with the rail ends. In this form of the invention the screws 44 are preferably secured slightly lower in the seat 42 than in the form shown in Fig. 2, for the 45 reason that as there is a slight divergence between the lower portions of the seat ends and the lower portions of the inclined faces of the corresponding lugs which is to be taken up by the tightening of the screws 50 and the wear resulting upon the parts, it is 55 advisable to secure a slightly greater leverage upon the depending lugs to force the same into contact with the seat ends throughout a substantial portion of the area of the 60 seat ends.

While Figs. 3 and 4 show a form of structure in which the angle of inclination of the seat ends is somewhat greater than the angle of inclination of the corresponding faces of the depending lugs, the lugs are forced into 70 contact with a substantial portion of the inclined ends of the seat when the fastening or tensioning devices employed are properly tensioned, and the surface of contact between the inclined ends of the seat and the 75 inclined faces of the lugs constantly increases as the parts become worn and further tensioning of the fastening devices becomes necessary.

In Figs. 6 and 7 is shown one form of my 80 invention in which the same may be applied to existing structures such as street railway rails to afford a resilient support for the meeting ends of the rails. In the above-named figures 50 and 51 are adjacent rails 85 having abutting ends 52 and 53 respectively, the said rails being supported adjacent to their meeting ends by cross-ties 54 and 55, while, as in the structures previously shown, the meeting ends of the rails are connected 90 by fish plates or rail splices 56 and 57 positioned upon opposite sides thereof and connected together by bolts 58 passing through the web portions 59 of the rails. The fish plates or splices 56 and 57, as shown, are of 95 the form commonly employed for connecting rails of this type, and, while I propose to apply my improved joint to rails of this character by forming the depending lugs integral with the fish plates or splices, after 100 the manner shown in connection with the common type of railway rails, I also contemplate applying the same, particularly in connection with rail structures already in use, by securing supplemental plates 60 and 61 to 105 the outer faces of the fish plates or splices 56 and 57, the plates 60 and 61 being each provided with inwardly extending depending lugs 62 and 63 respectively for supporting a seat beneath the meeting ends of the rails. 110 By applying the invention to existing structures after the manner described, it will be unnecessary to remove the fish plates or splices now in use, and necessary only to remove the bolts 58 located adjacent the meeting ends of the rails and, after placing the plates 60 and 61 in position against the outer faces of the fish plates pass the bolts again through the registering openings in the fish plates, rail web, and plates 60 and 61, 115 whereupon the plates 60 and 61 may be firmly and rigidly secured to the fish plates and form therewith what is in effect an integral structure.

Each of the depending lug portions 62 and 63 is provided with an inclined inner face 65 for contact with one of the inclined ends 66 of a seat 67 positioned between the depending lugs. The angle of inclination of the seat ends from the vertical may be some- 120 125 130

what greater than the angle of inclination of the inner faces of the depending lugs as shown in the drawings, and a bolt 68 is passed through openings 69 in the opposite lugs, the openings 69 being so formed as to permit slight vertical movement of the bolt 68 relative to the depending lugs, as in Figs. 2-4 previously described.

The seat 67 is provided with a recess 70 formed in the base thereof for the reception of the bolt 68, after the manner shown in Figs. 3 and 5 of the drawings.

The bolt 68 has a head 71 which bears against a washer 72 located outwardly of one of the depending lugs, while a nut 73 threaded upon the opposite end of the bolt bears against a similar washer 72 located outwardly of the other depending lug. Each of the depending lugs is provided upon its outer face with an inwardly inclined surface 75 adjacent to the upper edge of the washer 72, and a second inclined surface 76 located adjacent the lower edge of the washer, the angle of inclination of the surface 76 from the vertical being somewhat greater than the angle of inclination of the surface 75. Each of the washers 72 may be provided with a curved shoulder 77 for contact with the inclined surface 76 to increase the upwardly creeping action of the washers when pressure is exerted thereon by tightening the nut 73 on the bolt 68.

In this form of the invention, as in that shown in Fig. 3 of the drawings, the slight difference between the inclination of the ends of the seat and the corresponding inclined faces of the lugs is preferably only sufficient to permit the depending lugs to spring inwardly slightly as the ends of the seat wear and as greater tension is placed on the lugs by tightening the nut 73 so that the inner inclined faces of the depending lugs shortly contact with a substantial portion of the inclined ends of the seat.

While I propose to apply my invention to street railway rails by forming the depending lugs integral with the fish plates employed for connecting the meeting ends of the rails, I have shown in Figs. 6 and 7 one form in which the same may be readily applied to existing structures or with the type of fish plates or splices already in use without the necessity of any modification in the form and arrangement of the parts as now employed, thus greatly reducing the initial cost of installation without sacrificing any of the advantages obtained.

In the usual and ordinary form of rail joint now in use the passage of heavy loads causes great strain to be exerted upon the fish plates and the bolts connecting the same through the web of the rail, and continued use under traffic conditions results in the head of each rail end being forced against the head flange of the fish plate at the point

indicated by A in Fig. 2 until a depression is frequently formed in the head flange of the fish plate or the lower face of the rail head becomes worn which increases the vibration of the rail end and continued use sometimes results in the breaking of the rail, the bending of the fish plates and the placing of undue strain on the connecting bolts, causing what is commonly known as low joints.

In each form of the invention as above described, the difficulties mentioned are overcome to a considerable degree since the strain ordinarily exerted upon the flanges head is largely communicated through the web of the rail from the base of the rail to the seat and thus to the depending lugs of the fish plates, this being effected through the comparatively large area of contact between the inclined ends of the seat and the inclined faces of the depending lugs. Moreover the pressure exerted upon the seat tends to relieve the longitudinal strain upon the bolts connecting the fish plates through the web of the rail and thus effect an equalization of the strain upon the various parts of the structure.

It will be noted that the seat shown in the various forms of the invention herein disclosed is movable vertically by reason of the oblong openings in the depending lugs whereby means is provided for taking up the wear occasioned by continued use and a support constantly presented to the rail ends as they vibrate under the influence of loads passing thereover, thus forming in effect a resilient support for the rail ends.

The openings formed in the depending lugs through which the screws or other fastening means pass, while preferably oblong as best adapted to permit vertical movement of the fastening devices, may be round or of any other desired shape so long as they permit free movement of the fastening devices vertically to a sufficient extent to permit the proper tightening of the fastening devices and the necessary vertical movement of the same to allow the seat to move upwardly into contact with the rail ends under the pressure exerted by the inclined faces of the lugs on the inclined ends of the seat.

While in Figs. 3, 4 and 7 the angle of inclination of the seat ends is shown as somewhat greater than the angle of inclination of the inclined faces of the lugs, it is to be understood that these figures show the position of the parts before the lugs have been fully tensioned, and, in consequence thereof, a somewhat larger bearing surface will be had between the inclined faces of the depending lugs and the inclined ends of the seat when the parts are under the required tension than is illustrated in the above mentioned figures, thus obtaining in these forms

of the invention a substantial bearing surface between said seat ends and the inclined ends of the lugs.

While I have shown and described in considerable detail certain precise forms of my invention, it will be evident from the foregoing description that various changes may be made in the proportions of the elements and arrangement of the parts such as will occur to one skilled in the art in adapting the same for varying conditions of use, and it is not my intention to be limited to the precise proportions of the elements as shown nor their exact form and arrangement except as the same may be defined by the appended claims when properly construed in the light of my invention.

What I claim is:—

1. In a rail joint structure, the combination with adjacent rails, of a vertically movable seat provided with inclined ends, fish plates positioned upon opposite sides of said rails, lugs depending from said fish plates and having inclined faces contacting with the inclined ends of said seat, the angle of inclination of each seat end being substantially the same as the angle of inclination of the contacting face of the corresponding lug whereby each seat end will have a comparatively large surface of contact with the inclined surface of the contacting lug when the lugs are held in gripping engagement with the seat ends, and means for holding the depending lugs into contact with said seat ends while permitting slight vertical movement of said seat relative to said depending lugs.

2. In a rail joint structure, the combination with adjacent rails, of a vertically movable seat located beneath the meeting ends of said rails and provided with inclined ends, fish plates positioned upon opposite sides of said rails, lugs depending from said fish plates and having inclined faces contacting with the inclined ends of said seat above the center of gravity thereof, and means for forcing the lugs into gripping engagement with said seat to normally hold the seat in contact with the rail ends.

3. In a rail joint comprising a pair of abutting rail ends, fish plates positioned upon opposite sides of said rails, lugs depending from said fish plates and having inwardly inclined faces, a seat located beneath the meeting ends of said rails and having inclined ends contacting with the inclined faces of said lugs, washers seated against the outer faces of said depending lugs and contacting with inclined seating surfaces upon the outer faces of lugs whereby upward movement of said seat into contact with said rail ends is promoted, and holding means for

exerting pressure upon said washers to force the depending lugs into gripping engagement with the inclined ends of said seat and through the cooperative action of said washers and lugs urge the seat upwardly into contact with said rail ends. 65

4. In a rail joint comprising a pair of abutting rail ends, fish plates secured to opposite sides of said rails, a lug extending downwardly from each fish plate, a vertically movable seat located beneath the meeting ends of said rails and having its end portions contacting with the inner faces of said lugs throughout a substantial portion of the area of said seat ends, and means for forcing said lugs into gripping engagement with said seat ends while permitting slight vertical movement of said seat relative to said lugs. 70 75

5. In a rail joint comprising a pair of abutting rail ends, fish plates secured to opposite sides of said rails, lugs extending downwardly from said fish plates and provided with inclined inner faces, a resiliently mounted seat located beneath the meeting ends of said rails and having its end portions contacting with the inner inclined faces of said lugs above the center of gravity of said seat, and means for forcing said lugs into gripping engagement with said seat ends while permitting slight vertical movement of said seat relative to said lugs. 85 90

6. In a rail joint comprising a pair of abutting rail ends, plates secured to opposite sides of said rails and provided with integral depending lugs having inclined inner faces, a seat located beneath the meeting ends of said rails and having inclined end portions contacting with the inner inclined faces of said lugs above the center of gravity of said seat, and means for holding said lugs in gripping engagement with said seat ends while permitting slight vertical movement of said seat relative to said lugs. 95 100 105

7. In a rail joint structure, the combination with adjacent rail ends, of a vertically movable seat located beneath the meeting ends of said rails and provided with inclined ends, a pair of fish plates secured to opposite sides of said rails, supplemental plates contacting with said fish plates and firmly secured thereto, lugs depending from said supplemental plates and provided with inclined inner faces, and means for drawing said depending lugs into gripping engagement with said seat ends while permitting slight vertical movement of said seat relative to said lugs. 110 115 120

In testimony whereof I have affixed my signature.

JOHN W. CLARK.
